DESIGN FOR A KITCHEN REMINDER

Gale M. Spowers, Crisfield, Md., assignor to Chas. D. Bridgell, Inc., Crisfield, Md., a corporation of Maryland

Application April 11, 1940, Serial No. 91,609

Term of patent 3½ years

To all whom it may concern:

Be it known that I, Gale M. Spowers, a citizen of the United States and a resident of Crisfield, in the county of Somerset, State of Maryland, have invented a new, original, and ornamental Design for a Kitchen Reminder, of which the following is a specification, reference being had to the accompanying drawing, forming a part thereof.

In the drawing:

The figure is a front elevational view of a kitchen reminder, showing my new design.

The article is relatively thin and its back is flat and unornamented.

I claim:

The ornamental design for a kitchen reminder, as shown and described.

GALE M. SPOWERS.
